UNITED STATES PATENT OFFICE.

JOHN M. RICHARDSON, OF MILWAUKEE, WISCONSIN.

DAVENPORT.

1,288,682.

Specification of Letters Patent. Patented Dec. 24, 1918.

Application filed July 6, 1918. Serial No. 243,594.

To all whom it may concern:

Be it known that I, JOHN M. RICHARDSON, a citizen of the United States, and resident of Milwaukee, in the county of Milwaukee and State of Wisconsin, have invented certain new and useful Improvements in Davenports, and I do hereby declare that the following is a full, clear, and exact description thereof.

10 My present invention relates to new and useful improvements in foldable couch beds or davenports, more particularly of that type wherein the seat member of the davenport may be swung outwardly to form one 15 of the bed bottom sections.

It is in general the object of the invention to simplify and strengthen the structure of devices of this character, and to increase the 20 readiness with which they may be manipulated for their various uses.

It is a further and important object to provide an arrangement wherein the outward swinging movement of the seat member of the davenport forming the outer bed bottom 25 section procures a vertical movement of an inner bed bottom section carried within the davenport frame whereby both members lie in a common raised plane in final bed-forming position, the inner bed bottom section 30 serving also to counter-balance the outer section in its swinging movement, whereby to facilitate manipulation thereof.

A more detailed object in this connection resides in a provision of an arrangement for 35 locking the inner bed bottom section against retracting movement by the outer section in its bed-forming position whereby collapse of the bed is prevented except upon positive upward swinging movement of the outer bed section.

40 A common difficulty encountered in davenport structures of this type is the damage caused to the front edge face of the seat structure when the seat structure is swung outwardly and downwardly, by engagement of said face against the front of the davenport frame. It is a further object of the present invention to provide an arrangement whereby such damage is avoided, and it is 45 more particularly the object to provide a facing member movable upon movement of the seat member to a position wherein any contact with its finished face is avoided.

50 A further object resides in the provision 55 of a counter-balancing means for lifting the

back member of the davenport, and holding it in lifted position in the use of the davenport as a bed.

With the above and other objects and advantages in view, the invention resides more particularly in the novel combination, formation and arrangement of parts herein-after described and pointed out in the appended claims.

In the drawing, Figure 1 is a vertical sectional view through a davenport embodying my invention, with the parts thereof in couch forming position.

Fig. 2 is a vertical sectional view through the davenport with the parts thereof in bed-forming position.

Fig. 3 is a fragmentary rear elevation of the lower portion of the davenport.

Referring now more particularly to the accompanying drawings, the davenport 75 frame in the present embodiment of my invention comprises a pair of side walls 5, having their upper forward portions suitably shaped to provide arm rests and connected at their upper rear corners by a top sill 6. A 80 connecting beam 7 for the side walls 5 is secured thereto against lower portions of their inner faces by bolts 8 passed longitudinally through the beam and through the walls.

The back member B of the davenport is 85 movable vertically from a normal position in the davenport frame, and to support the back member and effect this vertical movement thereof, a link 9 is pivoted to the intermediate portion of each end of the back member, 90 and in the normal position of the back member inclines upwardly and rearwardly therefrom and is pivotally mounted on its upper end on a pivot rod 10 extending between the walls of the frame. Pivoted to the lower 95 portion of each end of the back member B is a lever 11 which also extends upwardly and rearwardly and has its intermediate portion mounted on a second pivot bar 12 extending between the walls. Thus the back member may be swung from a position resting against and inclined downwardly from the top wall 6, to a position wherein its upper portion is raised above the top 6. For effecting this swinging movement of the back member, links 13 are secured to the rear ends of the intermediately pivoted levers 11 and extend downwardly to the lower portion of the frame, being provided at their lower ends with longitudinal slots 14, re- 105 110

ceiving stop pins 15 which are movable into forward extensions 16 of the lower extremities of the slots. Retractile springs 17 have their upper ends connected with the upper 5 portions of the links, and have their other ends secured to the side walls 5 at points 18 rearwardly of and adjacent to the lower ends of the links.

The springs thus counter-balance the 10 weight of the back member B and possess such additional strength as to lift the back member to its raised position upon release of the pins 15 from the extensions 16 of the slots. This releasing movement is effected 15 by means of levers 19 intermediately secured on a rock shaft 20, and having their upper ends engageable with the links, their lower ends terminating in large forward pedal extensions 19^a, either of which may be depressed by an operator's foot inserted in the usual cutaway portion of the side wall. This lifting movement of the back member 20 provides clearance for the swinging movement of the seat member to bed forming 25 position.

Taking up now the bed bottom and seat structure, there is provided an inner bed bottom section 21 which, when the davenport is used as a couch seats on the beam 30 7 and which is of such width that its rear edge in the present instance projects a considerable distance rearwardly of the lower portion of the back member B. Secured to each end of the bed bottom section at its 35 rear is a link 22 which is pivoted on a bolt 23 mounted in a recess 24 cut into the upper portion of the said beam 7. Intermediately pivoted to the forward portion of each end of the bed bottom section is 40 a lever 25 which has its lower end pivoted in a recess 26 similar to the pivot recess of the link 22, the links and levers being inclined rearwardly in the seated position of the bed bottom section on the beam 7. Thus, 45 the bed bottom section may be swung upwardly and forwardly whereby its forward edge projects from the walls 5. Secured at its forward bottom edge to the forward top edge of section 21 by means of hinges 50 27 is an outer bed bottom section 28 which is adapted to seat on the bed bottom section 21 and which has a seat cushion S mounted on its face uppermost in this position. Secured to the forward portion of each end of this 55 bed bottom section 28 is a link 29 which extends rearwardly and is provided with a longitudinal slot 30 in its rear end in which is mounted a pin 31 carried on the upper end of the adjacent lever 27.

60 Thus, upon swinging the bed bottom section 28 upwardly, the pin will ride in the slot 30 until it engages the end of the slot and the section 28 has assumed a substantially vertical position. Further swinging 65 movement of the section 28 will then raise

the section 21 on its pivot mountings to the position heretofore described, the complete swinging movement of the section 28 being through an arc of 180° whereby it lies in the raised plane of the section 21 to thus 70 form a bed located at a comfortable elevation.

To provide a facing for the front of the davenport in its couch forming relation of parts which will not be injured upon disposition of said parts in bed forming position, a facing plate 32 is provided having its lower edge hinged at 33' to the edge of the beam 7, this plate being of such width as to extend to the meeting plane of the bed 80 bottom sections in their couch forming relation. Links 33 are pivoted to the intermediate portions of the ends of the plate and to the levers 25. So far as the connections of the links 33 with the levers 25 are 85 concerned, the levers may discharge simply the functions of links such as the links 22 in the possible event that any means for lifting the inner bed bottom section is employed, other than the means shown. Hence 90 in this respect the term links may be applied to the members 25 with respect to their portions between the bed bottom and connecting beam pivots.

Thus, as the sections are swung to bed 91 forming position, the plate 32 will be swung outwardly, affording ample clearance for movement of the section 21. The forward edge of the section 21 thus need not be provided with a finished surface, since it is, in 100 retracted position, disposed behind the face of plate 32 and this forward surface is of such nature as not to damage the finished forward edge surface of the section 28 when it is swung to a position opposite thereof. 105

A comparatively simple davenport structure has thus been provided wherein an economy particularly of metal parts may be effected, since the seat box forms one of the bed bottom sections. The structure may be 110 most readily and conveniently operated, it being noted that the outer bed bottom section 21 does not exert any lifting action until it has reached a substantially vertical position, and then the lifting action exerted 115 thereby on the section 21 procures a counter-balance of these parts.

It will be further noted that as the bed bottom section 28 moves to bed forming position, the links 29 move past the pivot connections of said section. Thus, a positive lock is afforded against collapsing movement of the sections, it being noted that forward movement of the sections past proper bed forming position is prevented by an abutment of the links 22 and levers 25 against the forward vertical walls of their pivot recesses 24 and 26.

What is claimed is:

1. A foldable couch bed including a main 130

frame, a bed bottom section, levers intermediately pivoted to the bed bottom section, the lower ends of said levers being pivoted to the frame, a second bed bottom section hinged at one edge to an edge of the first named bed bottom section, links pivotally secured to the second bed bottom section adjacent its hinged axis and having pivotal connections with the other ends of the levers, and said links being movable past the hinge axis of the second bed bottom section in final swinging movement of said section.

2. A foldable couch bed including a main frame, a bed bottom section therein, pivot links connecting the bed bottom section and frame and mounting said bed bottom section for movement thereof upwardly and forwardly with respect to the frame, a second bed bottom section hinged at its lower forward edge to the upper forward edge of the first bed bottom section, a facing plate adapted for disposition at the forward face of the first named bed bottom section in retracted position thereof, and hinged at its lower edge to the frame, and links pivoted to the facing plate and to adjacent first named links.

3. A foldable couch bed including a main

frame, a bed bottom section, a pivotal support carried by said frame for said bed bottom section permitting movement of the section upwardly and outwardly toward the front of the frame, a combined bed bottom and seat section hinged at the lower portion 35 of its front edge face to the upper portion of the front edge face of the first named bed bottom section, the front edge face of the combined seat and bed bottom section being exposed when the said section is swung inwardly and downwardly, a shield plate 40 hinged adjacent its lower edge to the front portion of the main frame below the first named bed bottom section and normally covering the front edge face of the first 45 named bed bottom section with its upper edge terminating substantially at the lower margin of the front edge face of the bed bottom and seat section in downwardly swung position of said first named bed bottom section, and means for procuring movement of the shield plate upon movement of the first named bed bottom section.

In testimony that I claim the foregoing I have hereunto set my hand at Milwaukee, 55 in the county of Milwaukee and State of Wisconsin.

JOHN M. RICHARDSON.
